UNITED STATES PATENT OFFICE.

ALBERT E. GRANT, OF TROY, NEW YORK, ASSIGNOR TO JOHN MOIR GRANT, OF PITTSBURGH, PENNSYLVANIA.

DEVICE FOR SEPARATING METAL SHEETS.

1,109,676.

Specification of Letters Patent.

Patented Sept. 8, 1914.

Application filed December 18, 1912. Serial No. 737,384.

To all whom it may concern:

Be it known that I, ALBERT E. GRANT, a citizen of the United States of America, residing at the city of Troy, in the county of 5 Rensselaer and State of New York, have invented certain new and useful Improvements in Devices for Separating Metal Sheets, of which the following is a specification.

- 10 My invention relates to devices for separating metal sheets, and the object of my invention is to provide a machine for opening a pack of metal sheets and delivering each separate sheet from the machine; together with such elements and combinations as are hereinafter more particularly set forth and claimed. I accomplish these objects by means of the mechanism illustrated in the accompanying drawings, in which:—
- 15 Figure 1 is a plan of the machine. Fig. 2 is a side elevation. Fig. 3 is an end view. Fig. 4 is an enlarged section along the line A—A on Fig. 2. Fig. 5 is an elevation of the vacuum cup and clamps. Fig. 6 is a 20 plan of the vacuum plunger. Fig. 7 is a detail view of the segment gear and its connections. Fig. 8 is a detail view of the pinch rollers, showing their position when the metal sheets are first put in the machine.
- 25 Fig. 9 is a detail view, showing the position of the pinch rollers after the metal sheets have been operated upon by them. Fig. 10 is a detail view with parts broken away, showing the track and the position of the 30 metal sheets as they are moved by the racks. Fig. 11 is a detail view of the pawl and trip mechanism. Fig. 12 is a detail view of the disks, 18 and 25, and manner of connecting them up.
- 35 40 Similar numbers refer to similar parts throughout the several views.

In the manufacture of metal sheets of light gage, tin plate, etc., it is the practice to double the sheets one or more times and roll 45 them together in what is known as a pack. A pack contains from two to eight or more thin sheets slightly stuck together in the process of rolling. The sheets in the pack are then separated, or, as generally termed, 50 "opened" by hand.

The machine is constructed essentially as follows:—The small idle rollers 1, 2 and 3, revolve in the notched slide, 6, and the rollers, 4 and 5, revolve in the two arms, 7,

which are held together by the plate, 8, see Figs. 8, 9 and 10. The arms with rollers, 4 and 5, are hinged on the trunnions of roller 3, and when the slide, 6, is drawn up the rollers, 9, also attached to the arms, 7, roll on the tracks, 10, shown in Figs. 9 and 10, 60 and cause rollers, 1, 2, 4 and 5, to come in contact with one another and pinch the end of the pack, as shown in Figs. 9 and 10 and by the dotted and dash lines in Fig. 2. The lever, 11, to which is attached the weight, 12, 65 is pivoted at 13, and is held in position by the set screw, 14. It is also connected by the rod, 15, to the lever, 16, which is pivoted to the bar, 17. This bar is held in a notch in the disk, 18, by the spring, 19, see Fig. 10. 70 The lower end of the lever, 16, is grooved to fit over the rod, 20, and is limited in its travel by a nut on the end of the rod. The other end of this rod is fastened to the arm, 21, which is fastened to the shaft, 93, see 75 Fig. 3. To this shaft is also fastened the long arm, 92. The other long arm, 91, is pivoted at 22. Both long arms extend up through a slot in table, 23, and are each held against the pack on the table by the springs, 80 24, see Fig. 2.

When the last sheet in the pack on the table has been taken away, the long arms are forced by springs to the end of their slots in the table, 23, and pull the nut on the 85 end of rod, 20, against the end of lever, 16. When a new pack is placed on the plate, 8, it slides down and strikes the end of lever, 11, which is forced back and pulls lever, 16, which pulls the bar, 17, from the notch in disk, 18, see Figs. 7 and 10. With this arrangement, or something of similar construction, the sheets in the pack on the table must be placed on the plate, 8, before the bar can be drawn from the notch in disk, 18. 90 The disk, 18, is in one piece with disk, 25, shown in Figs. 1 and 12, which is provided with a notch for the pawl, 26, and pivot, 27, see Figs. 2, 7 and 11, which is connected by the rod, 28, to the movable end of the table, 100 23, as shown in Figs. 2, 4 and 11, which swings about the pins, 29, and which is made yielding to accommodate different thicknesses of packs by the springs, 88, 89, and 95 90. When the bar, 17, is pulled from the notch in disk, 18, which is loose on the shaft, 30, it revolves on the shaft and lets the table drop down to a position shown by dotted

and dash lines in Fig. 2 and by full lines in Fig. 10, and which is limited by a stop.

When the disk drops it strikes the bar, 31, and pulls the clutch pin, 32, from its groove in the sliding clutch, 33, which is keyed to the shaft, 30. A spring causes the jaw of the clutch to engage with a notch in the pinion, 34, which is rotated backward and forward by the gear segment, 35, see Figs. 2 and 7. The relation of the gear segment and pinion is such that the pinion makes about seven-eighths of a revolution and only when the gear segment is in its extreme right-hand position can the jaw of the sliding clutch enter the notch in the pinion. When the gear segment throws to the left, when the clutch is in, it revolves the shaft, 30, to which is keyed the gear wheels, 36 and 37, and pawl arm, 38. The gears engage with the racks, 39 and 40, which are fastened to the slide, 6, see Figs. 1, 2, 7 and 10. The pawl arm brings the pawl behind the notch in the disk and when the gear segment, 35, travels to the right the pawl on arm, 38, engages with the notch in disk, 25, and brings disk, 18, and pivot, 27, up until the bar, 17, springs into the notch in disk, 18, see Figs. 10 and 11. At this point the pawl is released from its notch in disk, 25, by striking against the lug, 41, and is held in position by the bar, 17, in the notch in disk, 18, shown in Figs. 7 and 10.

In bringing the disk and pivot up, the movable end of the table, 23, which is connected to the pivot, 27, by the rod, 28, is also brought up and the bar, 31, is released and the clutch pin, 32, pulls the sliding clutch, 33, from the pinion, 34, which is then free to rotate backward and forward with the gear segment, 35.

The gear segment, 35, is keyed to the shaft, 42, to which is also keyed the arms, 43 and 44. The arms are rocked back and forth by the connecting rod, 45, which is pinned to the gear wheel, 46, keyed to shaft, 48, see Figs. 1 and 2. This gear is rotated by engaging with the pinion, 47, keyed to the shaft, 49, which is driven by means of the belt pulley, 50, (or a motor, an engine or any other convenient form of power), see Fig. 1. The upper ends of the arms, 43 and 44, are slotted to receive a sliding bearing which turns on the trunnions of the large roll, 51, and cause it to roll back and forth on the movable table, 23, which holds the pack to be separated. The large roll, 51, is held from slipping by the gears, 52 and 53, which are keyed to the trunnions of the large roll and engage with the stationary racks, 54 and 55. The rollers, 56 and 57, are loose on the trunnions of roll, 51, and are in contact with the rails, 58 and 59, which are stationary and prevent the large roll from being lifted from the pack on the table, 23. The shoe, 60, slides over the pack

on the table and is connected to the trunnions of the large roll, 51, by the rods, 61 and 62.

The surface of the idle roller, 63, which is supported by bearings in the rail, 58, and is given the desired tension by springs and set screws, is slightly below the top of the large roll, 51, and revolves only when it comes in contact with the roll, see Fig. 4.

The pinch rollers, 64 and 65, are driven by the sprocket chain or belt, 66, from a wheel keyed on the shaft, 49.

The stationary dogs, 67 and 68, are pivoted and fall behind the pack when slide, 6, brings it up and when it returns they pull it from between the rollers in the slide and hold it until the table, 23, forces it up in contact with the under side of roll, 51. It will be noticed that the pack of metal plates is delivered in a position diagonally to the axis of the machine, as is shown in Fig. 1, where the pack is illustrated by dash lines, 100. The pack is then held from being pushed forward by the arms, 91 and 92, by the lugs, 69 and 70.

Recesses are provided in the shoe, 60, and roll, 51, to allow them to pass over the lugs, 69 and 70, and the ends of arms, 91 and 92.

In the body of the large roll, 51, is a means for producing a vacuum, see Fig. 4, which pulls off the top sheet of the pack and holds it against the surface of the roll where it is held by a clamp. This consists of a rod, 71, held up by the spring, 72, which is strong enough to break the vacuum in the vacuum cup, 73, which is made of some pliable material, attached to the lower end of the rod, 71. To the rod is pivoted one end of a bell crank, 74, the other end being pivoted to the movable pin, 75. To the rod is also attached a collar, 76, as shown in Figs. 4 and 5, to which is pivoted one end of the toggles, 77 and 78, the other ends being pivoted to the ends of the bell cranks, 79 and 80, and the ends of the bell cranks are pivoted to the clamps, 81 and 82, which are given a parallel motion by the links, 83 and 84.

When the roll, 51, is in its extreme left-hand position, as shown by dash lines in Fig. 4, the movable pin, 75, strikes against a projection, 109, on the frame of the machine, and by the aid of the bell crank, 74, forces rod, 71, down, thereby opening the clamps and squeezing the air from the vacuum cup, 73, producing a vacuum. When the roll, 51, starts to the right the pin, 75, is released and the spring, 72, pulls up the rod, 71, and the vacuum cup, 73, which brings with it the corner of the top sheet, 110, in the pack. At the same time the clamps, 81 and 82, close and hold the sheet firmly against the surface of the roll, 51, and hold it there as it rolls toward the right, pulling a sheet with it from the pack which is held down to the table by the sliding shoe, 60, and by the

roll itself. When the roll, 51, has nearly reached its right-hand position, as shown in full lines in Fig. 4, the pin, 75, is pushed in by coming in contact with lug, 85. This releases the clamps, 81 and 82. The sheet being held by rolls, 63, the end springs up and is grabbed by the revolving rollers, 64 and 65, which pass it from the machine between the guides, 86 and 87. This is shown clearly 10 in Fig. 4. After leaving the machine the sheets are either piled or carried away by a conveyer.

I do not limit myself to the form or construction of the machine, as disclosed, be- 15 cause the roll, 51, may operate on a curved surface as well as on a straight surface, and in a vertical or inclined plane as well as in a horizontal plane. Nor do I limit myself to the manner of causing the pack to enter the 20 machine; nor the means for delivering the pack to the table, 23; nor the means for operating the machine.

What I claim as my invention and desire to secure by Letters Patent is:

25 1. A device for separating sheets of a pack, comprising a means for pinching and bending one corner of the pack, thereby loosening the sheets from each other at that corner; a vacuum cup; and means for bringing the vacuum cup in engagement with that corner of the sheets, one after another, that have been thus loosened.

2. A device for separating separate sheets of a pack of metal plates, comprising a yielding table; means for conveying the pack of sheets to the table; means for bending the ends of the sheets; a vacuum cup; means for applying said vacuum cup to one of the sheets and lifting said sheet from the pack; means for holding the other of said sheets than the one thus separated in position on the table until the separated sheet is entirely removed from the pack.

3. In a device for separating sheets of a pack of metal plates, means for conducting the pack to a yielding table; a yielding table; means in connection with said table for causing it to be moved in the same plane as said conducting means, whereby the pack 50 may be moved along said conducting means

onto said table; a vacuum cup; means for causing said vacuum cup to engage the upper sheet of the pack; means for causing said vacuum cup to lift said upper sheet and carry the same clear of the pack; means for 55 engaging said sheet after it has been separated from the pack; means for causing said vacuum cup to break its connection with the sheet, substantially as described.

4. In a device for separating sheets of a pack of metal plates, means for conducting the pack, comprising a plate upon which the pack is placed; a series of rollers adapted to engage and bend the ends of the pack when the plate containing them is moved toward a horizontal position; means for moving the pack held by the said rollers to a yielding table, substantially as described.

5. In a device for separating sheets of a pack of metal plates, a large roll; a table 70 over which it rolls; a sliding shoe; rods connecting said shoe to the trunnions of the said large roll; means carried by said roll for separating from the pack one of the sheets; and means for causing said shoe to hold the 75 remaining sheets of the pack on the table during the operation of the large roll.

6. A device for separating sheets of a pack of metal plates, comprising a plate adapted to raise the pack and hold it with one end 80 elevated above the other; a series of rollers so arranged and connected up that when the pack is moved toward the horizontal the rollers will grip the ends of the pack and bend the same; means for moving the pack as 85 thus held by the rollers toward a yielding bed; a yielding bed; means for engaging the pack and causing it to leave the rollers and rest upon the bed; mechanical means applied to the pack resting on the bed for 90 raising one end of one of the layers of said pack; means for guiding the raised layer of said pack away from the machine, substantially as described.

In testimony whereof I have affixed my 95 signature in presence of two witnesses.

ALBERT E. GRANT.

Witnesses:

BEULAH CARLE,
GRACE PRIOR.
